[57] CLAIM

The ornamental design for a framing member for windows and the like, substantially as shown and described.

DESCRIPTION

FIG. 1 is an isometric view of one embodiment of framing member of my invention.

FIG. 2 is another isometric view of the embodiment of FIG. 1, showing the other sides thereof.

FIG. 3 is a right side elevation of the embodiment of FIG. 1.

FIG. 4 is a left side elevation of the embodiment of FIG. 1.

FIG. 5 is a right side elevation of a second embodiment of the present invention, which is identical with the first embodiment except for the illustrated difference in the rear wall.

FIG. 1.

FIG. 5.

FIG. 3.
